EM 1194484-0002 Registered Design, (Royal King Ltd.), Mar. 12, 2010, [online], [retrieved on Apr. 7, 2014] Retrieved from the Community Design Database of the Office for Harmonization in the Internal Market using the Internet: <URL: <http://oami.europa.eu>>.*
(Continued)*Primary Examiner* — Robin V. Webster*Assistant Examiner* — Lavone D Tabor(57) **CLAIM**

The ornamental design for an oral care implement, as shown and described.

DESCRIPTION

FIG. 1 is a left front perspective view of an oral care implement according to the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the remainder of the oral care implement forms no part of the claimed design.
